UNITED STATES PATENT OFFICE.

WILLIAM CAHOON, JR., OF LITTLE ROCK, ARKANSAS, ASSIGNOR OF ONE-HALF
TO E. L. LEFEVRE, OF SAME PLACE.

TYPE-WRITING MACHINE.

SPECIFICATION forming part of Letters Patent No. 410,490, dated September 3, 1889.

Application filed July 27, 1888. Serial No. 281,212. (No model.)

To all whom it may concern:

Be it known that I, WILLIAM CAHOON, Jr., a citizen of the United States, residing at Little Rock, in the county of Pulaski, State of Arkansas, have invented certain new and useful Improvements in Type-Writing Machines, of which the following is a specification, reference being had therein to the accompanying drawings.

10 This invention has relation to that class of type-writers in which a segmental type-disk is employed.

The objects and advantages of the invention will hereinafter appear, and the novel 15 features will be particularly pointed out in the claims.

Referring to the drawings, Figure 1 is a plan of a type-writer constructed in accordance with my invention. Fig. 2 is a longitudinal vertical section on the line *x x* of Fig. 1. Fig. 3 is a front elevation of the feed-pawl mechanism in detail. Fig. 4 is a front elevation of the platen-releasing mechanism in detail, the platen being removed. Fig. 5 is a 25 sectional detail through the type-segment, its sleeve, and the spindle.

Like numerals of reference indicate like parts in all the figures of the drawings.

1 represents the base of the machine, which 30 is supported at suitable points by lugs 2.

3 represents a type-disk standard, which is secured to the base and centrally bored, in which is loosely mounted a spindle 4, having transversely-projecting lugs or pins 5.

35 6 represents the type-disk segment, which is provided in this instance with two rows of printing-characters 8 and 9, which may be small letters or upper and lower case letters, as desired. Depending from a type-segment

40 6 is a sleeve 7, which is adapted for the reception of the upper end of the spindle 4, and is longitudinally slotted to straddle or receive the pins 5, and has formed thereon two opposite annular collars 10. A partition 11 is ar-

45 ranged transversely upon the base 1 in front of the standard 3, and projecting upwardly and outwardly therefrom is a spring-arm 12, having a pin 13 at its free end, which takes into a depression formed in the upper end of 50 the spindle and serves as a bearing for said spindle.

14 represents the paper-roll, which is journaled in standards 15 at each end of the opposite longitudinal ribs 16, which together form the carriage of the machine, the carriage being mounted in ways 17, secured to the base and having one of its ribs provided with a feed-rack 18. A bail 19, journaled in the standards 15 of the carriage, is adapted to swing into contact with the roll 14 and secure the paper thereon.

20 20 represents the key-levers, which are provided with indicating and operating keys at their front end and are fulcrumed upon a transverse rib 21, extending across the base 1 65 of the machine. A bridge 22 extends across the levers from side to side of the base, and a spring 23 is interposed between each lever and the bridge 22 in rear of its fulcrum and serves to depress the rear end of the lever 70 when not otherwise influenced. Guide-pins 24 are arranged between the levers and, projecting upwardly from the base 1, serve to prevent lateral displacement of said levers.

Adjacent to the partition 11 and in front 75 thereof are arranged opposite standards 25. At the upper ends of each, and extending across the machine and the rear end of the case, are vertically-opposite horizontal plates 26, provided with opposite perforations 27, 80 in which are loosely mounted gravity stop-pins 28—one for each lever—the lower end of each pin resting upon its companion lever. When the levers are in their normal position—that is, with their rear ends depressed—the 85 upper ends of these stop-pins are about flush with the upper plate 26, and when said levers are depressed the pin resting thereupon is raised, all for a purpose hereinafter described.

90 Journaled in bearings 29 at each end of the partition 11 is a rock-shaft 30, which is provided with a forwardly-projecting bail 31, extending across the rear ends of the key-levers and resting thereupon, springs 32, connecting 95 the bail with the partition, serving to maintain the same in a lower position and in contact with the levers.

Mounted upon the rock-shaft 30, and adapted to move therewith, is a rock-arm 33, the 100 forward end of which may be extended and connected to the bail and the rear end of which

is longitudinally slotted, as at 34, and passing through said slot is a curved inclined arm 35, projecting from the spindle 4. The arm 35 is curved and depressed toward its lower end, 5 so that by depressing a key-lever, as shown in Fig. 2, its companion pin 28 will be raised and its rear end will raise the bail 31, which in turn will depress the slotted rock-arm 33 and cause the same to turn the arm 35 by 10 riding along its incline. The arm 35 being rigid with the post 4 and said post being in rotatable connection with the sleeve 7 by means of the pin 5, said sleeve will turn and carry with it the type-segment, thus presenting 15 the character thereon agreeing with the key 20 to the printing-point. This printing-point will be determined by reason of an arm 36, projecting from the rear end of the type-segment, coming in contact with the pin 28, 20 which is raised out of its normal position and into the path of said arm. When the key is released, the parts return to their normal position. The forward ends of the key-levers 20 are limited in their downward movement 25 by the transverse stop 37, arranged across the base of the machine, and are also limited in their upward movement by means of a spring-bail 38, the ends of which are connected to the ends of the stop 37 at each side of the machine, and which embrace the upper edges of 30 the key-levers.

Pivoted in bearings 39, depending from the under surface of the machine and preferably at one side thereof, is a lever 40, the key of 35 which projects up through the base within convenient distance of the hand of the operator. This lever extends to the rear of the machine and under the base to a point about opposite the standard 3. A sleeve 42 (see 40 dotted lines, Fig. 1) projects upwardly from the surface of the machine and under the type-segment, and mounted for sliding in the same is a vertical rod 43, the upper end of which is L-shaped and bifurcated and terminates between the annular collars 10, fixed 45 to the sleeve 7. The opposite end of the rod 43 rests upon the rear end of the lever, so that by depressing the lever 40 at its front end, through the medium of the key 41, the 50 rod 43 is raised, and with it the type-segment 6, thus presenting to the printing-point the lower row of printing characters, which may be small letters or capitals, as desired. At opposite sides of the base are posts 44, projecting 55 upwardly therefrom, and pivoted thereto are the opposite ends of a feed-bail 45, which extends transversely across the machine under the front end of the key-levers 20 and in the path thereof, said bail being yieldingly 60 supported in a raised position and in contact with the levers by a spring 46. Journalled in bearings 47 is a longitudinal rock-shaft 48, the front end of which is bent at an angle and terminates under and in the path of the 65 bail 45, and the opposite end of which is also bent at an angle and carries the pivot-pawl 49, the front end of which works in the teeth

of the rack-bar 18. A small spring 50 is interposed between the front end of the rock-shaft 48 and the base, and serves to maintain 70 the same in a raised position and against the bail 45. By this it will be seen that when a key-lever is depressed not only will the type-segment be operated to bring the desired character to the printing-point, but that the 75 pivoted pawl, which is provided with a hooked working end, will, when the lever is liberated, draw the carriage one tooth to the left and ready for the next impression. This return movement of the pawl is caused by a flat 80 spring 51, projecting under the pin 52^x.

In this machine I employ a movable platen 52 in preference to a movable roller, said platen being of an L shape and provided with an impression end 53, and the lower end thereof 85 being pivoted, as at 54, in standards 55, projecting upwardly from the base at its rear end and in line with the post 3. A spring 56, secured to the base projects upwardly therefrom, is curved, and terminates in a notch 57, 90 formed in the rear end of the movable platen 52 and in rear of its pivot 54, and serves, when not otherwise influenced, to force said platen to a forward position, so that its impression end 53 is brought against any printing character that is in line therewith. Formed upon the rear edge of the platen 52 are vertically-opposite cams 58 and 59.

Pivoted in rear of the platen 52 is a locking-pawl 60, upon the front face of which is 100 formed a locking-finger 61, adapted to take over the lower tooth or cam 59 of the platen, and is also provided with curved recessed portions 62 63 at each side of said finger 61. The locking-pawl 60 is maintained in a locked 105 position—that is, swung to the front—so that its finger 61 is over the tooth or cam 59, through the medium of a flat spring 64, secured to the frame-work and having its free end terminating in one of a series of notches 110 65, formed in the rear face of the locking-pawl.

Pivoted in hangers 66, depending from the under surface of the base of the machine, and about midway thereof, is a releasing-lever 67, 115 the forward end of which terminates about in a line with the bail 45, and from said bail there depends a pin 68, the lower end of which rests upon the lever 67, and the rear end of the lever 67 occurs about under the locking-pawl 60 and slightly at one side thereof. Pivoted to this lever 67, as at 68^x, is a tripping piece or lever 69, having vertically-opposite transversely-projecting pins 70 and 71, said lever projecting up through the base 120 of the machine and at one side of the locking-pawl. The upper pin 70 of the tripping-lever is longer than its companion, and when the platen 52 is in its normal position—that is, swung to the rear—said pin 70 rests directly 125 under the upper tooth or cam 58 thereof and within the depression 62 of the locking-pawl 60. Now when a key-lever is depressed the lever 67 is also depressed at its front end, and

its rear end consequently rises, the platen 52 being considered in a locked rearmost position. As the lever 67 is raised at its rear end, the arm 69 is consequently raised and the pin 5 70 forced upwardly and between the curved portion of the locking-pawl and the upper tooth 58 of the platen 52. This causes the locking-pawl to be swung to the rear, moving against the tension of its spring 64, and with- 10 draws the finger 61 from contact with the lower tooth 59 of the platen. The spring 56, when the platen is thus liberated, throws the same to the front, bringing its impression end 53 to the printing-point as the printing 15 character on the type-segment is brought to that point, so that a sheet of paper occurring between the same receives an impression from the printing character. The finger of the operator being removed from the key, the 20 spring 46 raises the bail 45, and with it elevates the pin 68. When this pressure is removed, a spring 72 interposed between the end surface of the base, the lever 67, and near the rear end of the latter, serves to return 25 said lever to its normal position. As the lever returns, the shorter arm 71 of the releasing-arm 69 engages with a rearwardly-projecting pin 73, projecting from the rear edge of the platen 52. This brings the platen to 30 the rear, and the finger 61 of the locking-pawl 60 takes over the tooth 59, and the platen is thus locked for another impression.

If it is desired to move the paper-carriage to the right for the purpose of correcting an 35 error, to begin a new line, or for any purpose whatever, it is only necessary to depress the small lever 74, pivoted in brackets 75 at the side of the carriage. This lever is connected by a link 76 to the feed-pawl 49, and by its 40 depression said pawl is raised from mesh with the rack-bar 18 of the carriage.

Mounted in standards 77 at each side of the printing-segment are inking-ribbon spools or drums 78, around each of which is wound 45 one terminal of one end of an ink-ribbon 79. The drums are provided with annular grooves, and extending from one to the other of said drums, and thus connecting the same, is an endless belt or cord 80. The cord 80 is connected by an arm 81 to the movable carriage 15, so that as the carriage moves in either direction the endless belt is also moved, which in turn rotates the drums or spools and winds the ribbon from one drum to the other. After 55 printing a line, the carriage being returned, and also rotated through the medium of the thumb-nut 82, the ribbon is wound upon the drum at the right of the machine, so that no special reversing mechanism for the ribbon 60 is required.

An arm 83 may project from any portion of the machine, and in this instance from the partition 11 rearwardly, and is bifurcated at its end, as at 84, to form a guide and support 65 for the ribbon, so that the same is always

held in contact with and in printing relation to the type-segment.

Projecting rearwardly from the pin 68 is a spacing-key rod 45, the operation of spacing being the same as described with regard to 70 printing.

Having described my invention and its operation, what I claim is—

1. In a machine of the class described, the combination of a standard, mounted on the 75 base and centrally bored, a spindle loosely mounted in the same, a type-segment provided with a sleeve mounted upon the spindle and adapted to rotate therewith, and a spring-arm having a pin bearing upon the top of 80 said spindle, substantially as specified.

2. In a machine of the class described, a type-segment mounted upon a spindle and a curved arm projecting from the spindle, in combination with a slotted arm, a rock-shaft 85 connected with the curved arm, and a key-lever for operating said rock-shaft, substantially as specified.

3. In a machine of the class described, a type-segment provided with a projecting arm 90 and mounted upon a spindle having a projecting curved inclined arm, in combination with a rock-arm having a slot adapted to operate the curved arm, and a key-lever adapted to operate the rock-arm, and a stop to be 95 projected in the path of the arm of the segment, substantially as specified.

4. In a machine of the class described, a pivoted platen provided with an impression-end, an impelling-spring, and with cams, in 100 combination with a spring-pressed pawl having a finger for locking over one of said cams, and a releasing-arm, and a key-lever for operating said arm, substantially as specified.

5. In a machine of the class described, a 105 pivoted platen having a spring arranged in rear thereof and provided with cams, in combination with a locking-pawl having a finger adapted to take over one of said cams and provided with curved portions at each side 110 of its finger, and a releasing-arm pivoted at one side of the locking-pawl and provided with a pin adapted to ride in the curved portion of the locking-pawl and release the same from the platen, substantially as specified. 115

6. In a machine of the class described, a pivoted platen provided with cams, a locking-pawl for the same, and a releasing-arm arranged at one side of the pawl, in combination 120 with a releasing-arm lever and a bail for operating said lever provided with a key, substantially as specified.

7. In a machine of the class described, a pivoted spring-pressed platen provided with 125 a pin and rearwardly-projecting cams, a spring-pressed locking-pawl provided with curved faces, and an intermediate finger for taking over one of the cams, in combination with a releasing-arm having pins, 130

one for liberating the platen from connection with the locking-pawl and one for contact with the rearwardly-projecting pin of the platen, whereby the latter is returned to a locked position, substantially as specified.

8. In a machine of the class described, the standard 3, centrally bored, having the spindle 4 mounted therein, provided with the arm 35, in combination with the bail 31, rock-shaft 30, the rock-arm 33, slotted, as at 34, and connected to said arm, and the key-levers 20, substantially as specified.
9. In a machine of the class described, the

platen 52, mounted in standards 55, notched, as at 57, having the spring 56, arms 73, and cams 58 and 59, in combination with the locking-pawl 60, having the spring 64, curved faces 30 and 63, and finger 61, and the releasing-arm 69, having the pins 70 and 71 for operating the same, substantially as specified. 20

In testimony whereof I affix my signature in presence of two witnesses.
